UNITED STATES PATENT OFFICE.

PHILIP H. SAMPSON, OF WAUKEGAN, ILLINOIS.

RAILROAD-TRACK CONSTRUCTION.

1,396,596.

Specification of Letters Patent. Patented Nov. 8, 1921.

Application filed January 5, 1921. Serial No. 435,190.

To all whom it may concern:

Be it known that I, PHILIP H. SAMPSON, a citizen of the United States, and a resident of Waukegan, in the county of Lake and State of Illinois, have invented a new and useful Improvement in Railroad-Track Constructions, of which the following is a full, clear, and exact description.

My invention relates to improvements in railroad track construction and it consists in the combinations, constructions and arrangements herein described and claimed.

An object of my invention is to provide a railroad track construction which has a novel means for keeping the two rails equidistant from each other at all times.

A further object of my invention is to provide a device of the type described which has a durable, but light tie construction which is relatively cheap to manufacture.

A further object of my invention is to provide a device of the type described which has a novel means for securing the rails to the ties.

A further object of my invention is to provide a device of the type described which has means for preventing the nuts on the bolts, which hold two sections of rails together, from becoming loosened.

A further object of my invention is to provide a device of the type described which is relatively cheap to manufacture, which is just as durable and strong as the present track construction, and which will not require as much attention to keep it in order as the present track construction requires.

Other objects and advantages will appear in the following specification, and the novel features of the device will be more particularly pointed out in the appended claims.

My invention is illustrated in the accompanying drawings, forming part of this application, in which—

Figure 1 is a plan view of the device, Fig. 2 is an enlarged section along the line 2—2 of Fig. 1,

Fig. 3 is an enlarged section along the line 3—3 of Fig. 1,

Fig. 4 is an enlarged section along the line 4—4 of Fig. 1,

Fig. 5 is an enlarged section along the line 5—5 of Fig. 1, and

Fig. 6 is an enlarged perspective view of portions of the device which are shown disassembled for clearness.

In carrying out my invention, I provide a plurality of ties 1 which are of novel construction. Each tie is formed from sheet metal and is U-shaped in cross section (see Fig. 4). The sides 2 and 3 of the tie 1 are bent inwardly at 4 and 5. Disposed in each of the ties 1 are two blocks 6—6 which are adapted to carry the rails 7 and 8. These blocks can either be made from some composition of matter or from wood. It will be seen that the blocks 6—6 are thoroughly protected from the ground by the metal tie 1, and they would therefore not deteriorate so rapidly as if they were resting on the ground. It will also be observed that the sides of the tie 1 tend to keep the blocks from sliding relative the tie. To further insure the blocks against being moved by the vibration of a passing train, the space 7 between the blocks can be filled with concrete or the like.

As all of the blocks 6 are of the same construction, I will describe the block which is shown in Figs. 3, 4 and 6. A portion of the block 6 is cut away which leaves a depression 8' in which is adapted to be disposed a rail holding plate 9. It will be observed that the upper surface 10 of the plate 9 is flush with the exposed upper surface of the block 6. The portion of the plate 9 which is adjacent the shoulder 11 of the block 6 has a groove 12 therein which is adapted to receive a flange of the rail. The plate 9 also has a hole 13 extending therethrough in which a second rail holding block 14 is adapted to be placed. It will be noticed that the block 14 rests upon the block 6, and has a groove 15 which is adapted to receive the other flange of the rail. When the blocks 6 and 14, and the plate 9 are assembled (see Fig. 3), spikes 16 are driven into the blocks 6, thus holding the rail in place. With the construction just described, the train when running over the rail 8 tends to hold the rail in place, as the weight of the train on the rail, which rests on the rail holding members 9 and 14, securely holds these members in place. The inwardly bent sides 4 and 5 have cut away portions 17 which are adjacent the rails 7 and 8 so as to permit the rails to rest entirely upon the blocks 6 (see Fig. 1).

Where two sections of the tracks 7 or 8 are united, there is disposed a wedge-shaped tie 18 which takes the place of the usual tie 1. The larger width of the tie 18 is posi-

tioned under the rails where the two sections are joined. In the ties 18 are placed rail supporting blocks 19 and 20 which are, except for a minor change, exactly similar to the blocks 6. The block 20 differs from the block 6 in that it has a rail holding block 21 which takes the place of the block 14. This block instead of having a spike driven through it, as is the case with the block 14, has an upwardly extending lug 22 through which a transverse hole is drilled for a purpose to be explained later.

The block 19 has all of its parts identical with the block 6 except in the shape of its member 23 which takes the place of the block 14. As will be noticed in Figs. 1 and 2, the member 23 has in addition to the block 14 a tongue 24 which has a hole 25 through which the lug 22 of the block 21 is adapted to extend. A bolt 29 is inserted in the hole of the lug 22 which securely locks the tongue 24 and the block 21 together. The member 23 has a nut locking plate 26 which is integral therewith and which has a plurality of square recesses 27 which are adapted to receive the nuts 28 of the bolts which secure the rail sections together, and thus prevent the bolts from becoming loosened due to vibration.

From the foregoing description of the various parts of the device, the assembling of the same may be readily understood. The ties are first laid down in the customary manner and in them are disposed the blocks 6. The plates 9 are then laid in the depression 8' of the blocks 6, and on them are placed the rails 7 and 8. The blocks 14 are thereupon inserted in the hole 13, thus securely clamping the rail to the plate 9. Spikes 16 are driven through the plate 9 and the block 14 and into the blocks 6. It will be understood that a tie 18 is placed wherever two rail sections are joined together. The member 23 is used in place of the block 14 when the tie 18 is used, and acts as a spacer between the two rails and as a means for preventing the rotation of the nuts on the bolts which join the two sections of the rail together. After the device has been assembled, the space between the blocks which support the rails can be filled with concrete.

As will be obvious from the foregoing description, this device has ties which cannot deteriorate, it has a novel means whereby the rails are secured to the ties, and it has a novel means for always keeping the rails equi-distant from each other and for locking

the nuts on the bolts which join the rail sections together.

I claim:

1. In a railroad track construction, a hollow tie, blocks disposed in said ties, a rail carried by each block, rail-holding plates carried by said blocks and so disposed that the rail rests on a portion of each plate, one of said plates having an extension, said extension being adapted to extend between said blocks, and means for securing the free end of the extension to the plate carried by said oppositely disposed block.

2. In a railroad track construction, a hollow tie, a block disposed at each end of said tie, a rail carried by each block, a pair of rail holding plates carried by each block and so disposed that the rail rests on a portion of each plate, one of said plates having an extension adapted to extend between said blocks, and means for securing the free end of the extension to one of said plates carried by the adjacent block.

3. In a railroad track construction, a hollow tie, a block disposed at each end of said tie, a rail carried by each block, a pair of rail holding plates carried by each block and so disposed that the rail rests on a portion of each plate, one of said plates having an extension and a nut locking means, and means for securing the free end of the extension to one of said plates carried by the adjacent block.

4. A track construction comprising a plurality of hollow ties, a pair of blocks disposed in each tie adjacent the ends thereof, rail sections carried by said blocks, means for securing said rail sections together, and a wedge-shaped hollow tie disposed beneath the joining of said rail sections, the wider end of said tie being positioned beneath the joining of the two rail sections.

5. A railroad track construction comprising two parallel rails, each rail made up of joined sections, the joinings in one rail being staggered with respect to the joinings in the other rail, a plurality of hollow ties, blocks disposed in said ties and being adapted to support said rails, a plurality of hollow wedge-shaped ties having wedge-shaped blocks disposed therein, said wedge-shaped blocks being adapted to support said rails, the wider end of said wedge-shaped ties being disposed beneath a joining of two sections of rails, whereby two adjacent wedge-shaped ties have their wider ends extend in opposite directions.

PHILIP H. SAMPSON.
